UNITED STATES PATENT OFFICE

JOHN K. RIDDLE, OF TOLEDO, OHIO, ASSIGNOR TO THE EDWARD N. RIDDLE COMPANY, OF TOLEDO, OHIO, A CORPORATION OF OHIO

LIGHTING FIXTURE

Application filed April 18, 1928. Serial No. 270,816.

This invention relates to lighting fixtures, and has for its object to improve the construction and arrangement of the various parts thereof in such a manner as to simplify their manufacture, facilitate their assemblage and installation, and otherwise increase their commercial value.

The detailed construction of the invention, as applied to electric lighting fixtures adapted to be suspended from a ceiling by a chain or other suitable means, and the advantages resulting from such construction, will be more particularly explained in connection with the accompanying drawings, in which:

Fig. 1 is a side elevation of one form of fixture embodying the invention.

Fig. 2 is a horizontal section taken on the line 2—2 of Fig. 1.

Fig. 3 is a vertical section taken on the line 3—3 of Fig. 2.

Fig. 4 is a partial section taken on the same plane as Fig. 3, illustrating the manner of assembling the fixture.

Fig. 5 is a plan view of the spider as indicated by the line 5—5 on Fig. 4.

Fig. 6 is a detail sectional view taken on the line 6—6 of Fig. 3.

Fig. 7 is a plan view of a spider adapted to be used with another form of the invention, a portion also of the bottom plate being shown in connection therewith, as indicated by the line 7—7 in Fig. 9.

Fig. 8 is a vertical section taken on the line 8—8 of Fig. 7, showing the complete assembly.

Fig. 9 is a partial sectional view taken on the same plane as Fig. 8, illustrating the method of assembling the fixture.

In the specific embodiment of the invention illustrated in Figs. 1 to 6, inclusive, a shell 1 is formed centrally with an upstanding eye 2 by means of which it may be suspended from the ceiling. This shell is connected to a bottom plate 3 by a series of braces 4 which are adapted to be shaped so as to form a suitable ornamental design. For convenience in assembling these parts, the shell 1 is formed with a series of equally spaced radial slots 5, corresponding in number to the number of braces 4. The ends of these slots di-

verge inwardly and the upper end of each brace 4 is formed with a toe 6 adapted to be inserted in the slot and having a forwardly projecting point 7 adapted to engage in locking relation with the outer end of the slot 5 when the brace is swung inwardly to the position shown in Fig. 3. The lower face of the shell 1 is curved downwardly to form an abutment for the opposed faces of the legs 4 and to hold them in locked position.

The bottom plate 3 is formed with a series of slots 8 adapted to receive the toes 9 formed at the lower ends of the braces 4. Each toe 9 is formed with a notch 10 which is adapted to engage the outer edge of the slot 8.

After the shell 1, brace 4 and plate 3 have been placed in assembled relation, a spider 11 is secured to the plate 3 by means of screws 12, the plate being formed with key-hole slots 13 for receiving the screws, in order to facilitate the assembling operation. The spider 11 is formed with upstanding lugs 14 adapted to engage behind the toes 9 and lock the latter in the slots 8.

The spider 11 is formed with a series of 75 radially extending arms 15 which have studs 16 or similar means at their outer ends for attaching electric light sockets thereto. Each arm is formed with a channel 17 which extends inwardly beneath the plate 3 and is adapted to receive the wiring. A clip 18 may be cast in the bottom of the channel 17, as shown in Fig. 6, for convenience in attaching the wire to the arm.

In the form of the invention illustrated in Figs. 7, 8 and 9, all of the various parts of the fixture are substantially the equivalents of corresponding parts in the assembly illustrated in Figs. 1 to 6 and are designated by the same reference numerals with the exponent "a" added. This embodiment comprises a shell 1^a having a central eye 2^a for suspending the same from the ceiling. A bottom plate 3^a is connected to the shell 1^a by means of braces 4^a.

The shell 1^a is formed with slots 5^a adapted to receive toes 6^a formed at the upper ends of the respective braces and having lips 7^a adapted to engage over the edges of the slots. In this form, however, the lower ends of the 100

braces are swung outwardly into locking position instead of inwardly.

The bottom plate 3^a is formed with peripheral radial slots 8^a adapted to receive toes 9^a formed at the lower ends of the braces 4^a, these toes being formed with notches 10^a adapted to engage about the inner edges of the slots 8^a.

The bottom plate 3^a is locked in assembled relation by means of a spider 11^a which is secured to the plate 3^a by means of a bolt 12^a. The spider is formed with shoulders 14^a adapted to engage behind the toes 9^a to lock the latter in position.

15 The spider 11^a is formed with radial arms 15^a terminating in sockets 16^a adapted to receive the electric lamps. The arms 15^a are formed with channels 17^a to receive the wires.

From the foregoing description it will be seen that in either of the forms herein shown and described the spider and bottom plate are supported directly from the shell by the braces without any central connecting rod or bar. The mere addition of the spider to the plate serves automatically to lock the braces both to the shell and to the plate so that no other means is required to support either the plate or the spider.

It will also be noted that the fixture is so constructed and assembled that the various parts may be easily cast or stamped and may be conveniently made in a great variety of attractive and ornamental designs. By such construction, both the manufacture and the assembly of the fixtures are greatly facilitated and their commercial value is increased.

It will also be understood that the distinctive features of the invention may be used in a great many different ways and their form and arrangement considerably modified without any material departure from the scope of the invention as claimed.

What I claim is:

1. In a lighting fixture, an upper member and a lower member, detachable means connecting said members and supporting one member from the other, a spider, means for attaching the spider to one of said members, and means rendered operative by bringing the spider into assembled position, to lock the connecting means to said members.

2. In a lighting fixture, an upper member and a lower member, detachable means connecting said members and supporting one member from the other, a spider, means for attaching the spider to one of said members, and means on the spider, engageable with the connecting means to lock the latter to each of said members, when the spider is secured by its attaching means.

3. In a lighting fixture, an upper member and a lower member, braces adapted to extend in radial planes and in divergent relation to each other from one of said members in supporting relation to the other, a spider,

means for attaching the spider to one of said members, and means, rendered operative by the attachment of the spider, to lock the braces to said members.

4. In a lighting fixture, an upper member and a lower member, each having slots therein, braces detachably connected with the slots in the respective members, a spider detachably connected to the assembly, and means on the spider, operable when the spider is moved to assembled position, to lock the braces in the slots.

5. In a lighting fixture, an upper member and a lower member, braces having at their ends interlocking engagement with the respective members and constituting means for supporting one member from the other, a spider, means for securing the spider to one of said members, and means, rendered operative by the securing of the spider, to positively secure the braces in their interlocking relation to said members.

6. In a lighting fixture, an upper member and a lower member, each having slots therein, braces formed at their ends with toes insertable into coengaging relation to corresponding slots in the respective members by swinging said braces in radial planes, a spider, means for attaching said spider to the assembly, and means on said spider to lock the braces in the respective slots, when the spider is attached, so as to support one of said members from the other.

7. In a lighting fixture, an upper member and a lower member, braces for connecting said members, coengaging means on said members and the respective ends of the braces rendered effective by swinging said braces in radial planes, to support one of said members from the other, a spider, means for securing the spider to the assembly, and means, rendered operative by the securing of said spider, to lock said braces in their supporting position.

8. In a lighting fixture, an upper member and a lower member, each having a series of slots arranged concentrically about its center, a series of braces each having toes at its ends engageable, by a predetermined relative movement of the brace and said members, in locking relation to corresponding slots in said members, and means attachable to one of said members and engageable with said braces to secure the latter in their locking relation to each member.

9. In a lighting fixture, an upper member and a lower member, each having a series of slots arranged concentrically about its center, a series of braces each having toes at its ends engageable, by a predetermined relative movement of the brace and said members, in locking relation to corresponding slots in said members, a spider, means for securing the spider to the assembly, and means, rendered operative by the securing of said spider, to

secure the braces in their locking relation to each member.

10. In a lighting fixture, an upper member and a lower member, each having a series of slots arranged concentrically about its center, a series of braces each having toes at its ends engageable, by a predetermined relative movement of the brace and said members, in locking relation to corresponding slots in said members, a spider, means for attaching the spider to one of said members, and means on said spider, operative when the spider is attached, to secure the braces in their locking relation to each member, so as to support one of said members from the other.

11. In an electric lighting fixture, an upper member, a lower member, detachable braces arranged about a central vertical axis and constituting the means for supporting one of said members from the other, means for simultaneously locking said braces in assembled relation to said members, radial arms associated with one of said members, each of said arms being formed with a channel extending longitudinally thereof for receiving wires, and means at the end of each of said arms for attaching an electric lamp.

12. In a lighting fixture, a supporting member, a spider, detachable braces arranged about a central vertical axis and constituting the means for supporting the spider from said supporting member, and means for securing the spider in fixed relation to the braces and simultaneously securing the braces in fixed relation to the supporting member.

13. In a lighting fixture, an upper shell, braces having upper ends so formed as to be insertable from beneath said shell into locking relation thereto, a spider, and a common locking member for securing the spider to the lower ends of all of said braces to be supported thereby and simultaneously fixing the locking relation of the braces to the shell.

14. In a lighting fixture, an upper shell having slots arranged about its center, braces having upper ends insertable from beneath said shell and movable into locking relation to said slots by swinging said braces in radial planes, a spider, and a common locking member for securing the spider to the lower ends of all of said braces to be supported thereby and simultaneously fixing the braces in locking relation to said slots in the upper shell.

15. In a lighting device, an upper shell, braces having upper ends so formed as to be insertable from beneath said shell into locking relation thereto, a spider, and means for securing the spider to the lower ends of said braces and simultaneously fixing the locking relation of the braces to the shell, said braces constituting the main supporting connection between said shell and said spider.

16. In a lighting device, an upper shell

having slots arranged in radial relation to its center, braces having upper ends insertable from beneath said shell and movable into locking relation to said slots by swinging said braces in radial planes, a spider, and means for securing the spider to the lower ends of said braces and simultaneously fixing the braces in locking relation to said slots in the upper shell, said braces constituting the main supporting connection between said shell and said spider.

In testimony whereof, I have hereunto signed my name to this specification.

JOHN K. RIDDELE.
